Patented Feb. 1, 1921.

UNITED STATES PATENT OFFICE.

ALBERT J. WINNIER, OF NATICK, AND WALTER E. ERICKSON, OF BROOKLINE,
MASSACHUSETTS.

INTERNAL-COMBUSTION ENGINE.

1,366,993.

Specification of Letters Patent.

Patented Feb. 1, 1921.

Application filed November 6, 1919. Serial No. 336,045.

To all whom it may concern:

Be it known that we, ALBERT J. WINNIER and WALTER E. ERICKSON, citizens of the United States, residing, respectively, at 5 Natick and Brookline, in the counties of Middlesex and Norfolk and State of Massachusetts, have invented new and useful Improvements in Internal-Combustion Engines, of which the following is a specification.

10 This invention relates to an internal combustion engine and particularly to a valve mechanism for said engine.

15 It is the object of the invention to provide a simple efficient slide valve for an internal combustion engine so constructed and installed that it is capable of automatically adjusting itself to compensate for wear without requiring the use of springs of any 20 kind.

25 In valves of this type it has hitherto been the practice, in an attempt to prevent leakage, to employ a plate which is forced against the valve by springs of various forms. The use of springs of any kind for 30 this purpose has been found impracticable as the engine often becomes so hot as to remove the temper from the springs, whereupon the plate will fail to function properly and leakage will occur around the valve the 35 result being that it is impossible to hold the desired compression within the cylinder of the engine. Furthermore, where there is always a pressure against the face of a slide 40 valve, it requires more power to operate the valve, the valve and contacting parts will wear more quickly and it is more difficult to distribute the lubricating oil over the surface of the valve.

45 It is an object, therefore, of this invention to eliminate these defects and thereby produce a more efficient engine and one capable of producing more power for the size of the cylinders.

45 The invention consists in the combination and arrangement of parts set forth in the following specification and particularly pointed out in the claims thereof.

50 Referring to the drawings: Figure 1 is a front elevation of the cylinder block casting of an internal combustion engine, the cover plate being removed and a portion of the valve housing being

broken away to more clearly illustrate the valve mechanism.

55 Fig. 2 is a vertical section taken on the line 2—2 of Fig. 1.

Fig. 3 is a detail horizontal section taken on the line 3—3 of Fig. 1.

60 Like numerals refer to like parts throughout the several views of the drawings.

In the drawings, 5 represents a cylinder block casting for an internal combustion engine of the four-cycle type, the cylinders and cylinder heads being cast integral. The 65 cylinder block 5 is formed with a pair of cylinders 6, each of said cylinders being provided with the usual water jacket 7, inlet port 8, exhaust port 9, and having a piston 10 adapted to reciprocate therein. An inlet 70 valve 11 is adapted to open the inlet port 8 at the proper time to admit an explosive charge to a combustion chamber 12 upon the interior of the cylinder 6 above the piston 10 during the suction stroke of the piston, and to close the inlet port 8 at the end of said suction stroke, the inlet port remaining closed during the succeeding compression, firing and exhaust strokes. An exhaust valve 13 is adapted to open the exhaust port 9 to allow the exhaust gases to 75 pass from the combustion chamber 12 during the exhaust stroke of the piston and to close the exhaust port 9 at the end of said exhaust stroke, the exhaust port remaining 80 closed during the succeeding suction, compression and firing strokes.

85 A suitable spark plug 14 is provided for the purpose of firing the explosive charge within the combustion chamber 12 at the proper time.

90 As the inlet and exhaust valves are identical in construction and operation, a description of one will serve also for the other.

95 The inlet and exhaust valves are located upon opposite sides of the cylinders 6 and each of said valves is adapted to reciprocate within a valve chamber 15 provided between a pair of oppositely disposed valve seats 16 and 17. The valve seat 16 is provided upon the outer face of the cylinder block 5 and a valve seat 17 is provided upon the inner face of a housing 18. The housing 18 is separated from the cylinder block 6 by a separator plate 19 which is provided 100 with openings formed therein, vertical sides

20 of said openings constituting side guides for said valves, and said separator plate cooperates with the valve seats 16 and 17 to form the valve chamber 15 for each of the 5 valves 11 and 13, the separator plate 19 entirely closing the sides and ends of said valve chamber.

Screws 21 simultaneously fasten the separator plate 19 and housing 18 to the side of

10 the cylinder block 5. The thickness of the separator plate 19 is preferably slightly greater than that of the valves 11 and 13, in order that said valves may slide loosely in their respective valve chambers. The 15 valves are each constructed without openings therein, the presence of which tends to cause a valve to warp, if overheated.

An upper edge 22 of each valve is so located that when said valves are in their 20 lowermost positions, the inlet port 8 and exhaust port 9 will each be wide open. A lug 23 is formed integral with each valve and projects at right angles outwardly therefrom through an opening 24 provided in 25 the housing 18. A valve stem 25 is adapted to slide longitudinally in a bearing 26 formed integral with the housing 18. The valve stem 25 is connected to the lug 23 passing through a slot 27 formed therein in 30 such a manner that the valves may automatically adjust themselves laterally upon the valve stems between the head of a stud 28 which has screw-threaded engagement with and constitutes a part of said valve 35 stem and a nut 29. This adjustment will allow the valves to compensate for wear and furthermore also allow the valves to reciprocate loosely within the valve chamber 15. The heavy lug 23 will also tend to carry 40 away and diffuse the heat from the valves. The lower end of the valve stem 25 has screw-threaded engagement with an eye-bolt 42, a nut 43 being provided to prevent said valve stem 25 from turning upon said eye-bolt. The eye-bolt 42 is connected by a connecting rod 30 with any of the well-known 45 types of valve driving mechanisms in common use.

The housing 18 is provided with a water 50 jacket 31, the water entering said water jacket through openings 32 from the water jacket 7 and returning through openings 33 to said water jacket 7. The two water jackets 7 and 31 provided upon opposite 55 sides of the valves act to cool said valves. The housing adjacent to the inlet valve 11 has formed integral therewith an inlet manifold 34, while the housing adjacent to the exhaust valve 13 has an exhaust manifold 60 35 also formed integral therewith. Cover plates 36 are provided fastened by the screws 21 to the housing 18 and by screws 37 to the cylinder block 5. These plates conceal the actuating parts of the valves and co- 65 operate with the walls of the housing 18 to

form a chamber 38 within said housing into which the lug 23 projects. Lubricating oil is forced under pressure through a pipe 39 into a cavity 40 formed in the housing 18 and thence through apertures 41 against the 70 slide valves 11 and 13, see Fig. 3, by which it is distributed by the movement of the valves over the surfaces of the valve chamber.

The general operation of our improved 75 device is as follows: Referring to Fig. 2, the inlet port 8 is wide open; the exhaust port 9 is closed with the exhaust valve 13 upon its upward stroke, while the piston 10 is moving downwardly upon the suction 80 stroke. As the piston 10 reaches the bottom of its stroke and starts upwardly the inlet port 8 will be suddenly closed and as the piston moves upwardly upon the compression stroke the pressure of the explosive 85 charge within the combustion chamber 12 will tightly force the valves 11 and 13 against the flat surface of the valve seat 17 and prevent any leakage around said valves. The greater the compression within the 90 combustion chamber the more tightly the valves will be forced against their respective seats 17. As the explosive charge is fired by the spark plug 14 forcing the piston 10 downwardly upon its firing stroke both 95 of the valves 11 and 13 will remain closed. As the piston arrives at the bottom of the firing stroke the exhaust valve will move downwardly opening the exhaust port 9 and as the piston 10 rises upon its exhaust stroke 100 it will force the burned gases outwardly through the exhaust port 9. The inlet valve 11 remains closed during the exhaust stroke of the piston but is suddenly moved downwardly to open the inlet port 8 at the beginning of the next suction stroke of the piston. With the exception of during the compression stroke and firing stroke of the piston there is no pressure against the sides of the valves 11 and 13 and consequently said 105 valves may be actuated very easily and with very little wear as the valves are loosely fitted in their respective valve chambers. At such times the lubricating oil which is forced under pressure into the valve chamber 15 is easily distributed by the movement 110 of the valves over the surface of said valves and said valve chamber. As the valves are forced against the surface of the valve seat 17 by the compression within the combustion chamber and later loosened when the pressure is withdrawn, the valves are at liberty to move laterally upon their respective valve stems and at such times may engage the surface of the valve seat 16. Furthermore, as the surface of the valves and the valve seats wear, the said valves may also move laterally upon the valve stems to automatically compensate for said wear. The water jackets 7 and 31 upon the oppo- 115 120 125 130

site sides of each of the valves act to cool the valves during the operation of the engine.

If it is desired to adjust the timing of the valves 11 and 13, it is only necessary to loosen the nut 43 from engagement with the lower end of the valve stem 25 and turn said valve stem in the proper direction to raise or lower the valve, whereby the desired result may be obtained.

Having thus described our invention what we claim and desire by Letters Patent to secure is:

1. An internal combustion engine embodying a pair of oppositely disposed valve seats with a valve chamber therebetween, a valve slideable loosely in said valve chamber and adapted to contact with either one of said valve seats, a lug projecting from the outer face of said valve formed integral therewith and provided with a slot therein, and means to actuate said valve, said means projecting through the slot formed in said lug, and being located entirely outside of the exhaust passage, whereby said valve may move laterally upon said actuating means to automatically compensate for wear.

2. An internal combustion engine embodying a pair of oppositely disposed valve seats with a valve chamber therebetween, a valve slideable loosely in said valve chamber and adapted to contact with either one of said valve seats, a water jacketed housing adjacent to the outer face of said valve provided with an opening extending therethrough, a lug projecting from the outer face of said valve through the opening in said housing, said lug being formed integral with said valve and being provided with a slot therein, and means to actuate said valve, said means projecting through the slot formed in said lug and being located entirely outside of the exhaust passage, where-

by said valve may move laterally upon said actuating means to automatically compensate for wear.

3. An internal combustion engine embodying a pair of oppositely disposed valve seats with a valve chamber therebetween, a valve slideable loosely in said valve chamber and adapted to contact with either one of said valve seats, a lug projecting from the outer face of said valve provided with a slot therein, and means located entirely outside of the exhaust passage to actuate said valve, said means including a valve stem projecting through the slot formed in said lug and rotatable therein whereby said valve may be positioned vertically within said valve chamber.

4. An internal combustion engine embodying a pair of oppositely disposed valve seats with a valve chamber therebetween, a valve slideable loosely in said valve chamber and adapted to contact with either one of said valve seats, a housing chamber, a lug projecting from the outer face of said valve into said housing chamber and provided with a slot therein, means located entirely outside of the exhaust passage to actuate said valve, said means including a valve stem projecting through the slot formed in said lug and rotatable therein whereby said valve may be positioned vertically within said valve chamber, and means to prevent the rotation of said valve stem within said lug.

In testimony whereof we have hereunto set our hands in presence of two subscribing witnesses.
